UNITED STATES PATENT OFFICE.

MELVIN E. HILL, OF LOS ANGELES, CALIFORNIA.

SHOE-CLEANER.

1,172,707.

Specification of Letters Patent. Patented Feb. 22, 1916.

Application filed October 12, 1915. Serial No. 55,571.

To all whom it may concern:

Be it known that I, MELVIN E. HILL, a citizen of the United States, residing at Los Angeles, in the county of Los Angeles and State of California, have invented new and useful Improvements in Shoe-Cleaners, of which the following is a specification.

My invention relates to shoe cleaners adapted to effectively clean mud, dust, dirt and the like from the sole and sides of a shoe in a convenient and efficient manner.

It is an object of this invention to provide a shoe cleaner adapted for cleaning a shoe while it is on the wearer's foot, such a device being particularly designed to be placed at the house-door or at any other convenient location in order that each person may thoroughly clean his shoes before entering, and the device is so constructed that the operation of cleaning may be quickly and effectively accomplished with the expenditure of a minimum amount of muscular effort.

Another object of this invention is to provide a shoe cleaner inclosed in a suitable housing and provided with brushes which are given a rotary motion by pressing the foot down upon the middle portion of the device.

Another object of this invention is to provide means for removing the dirt and dust accumulated within the device.

With these and other objects in view which will appear as the description proceeds, the invention resides in the combination and arrangement of parts and in the details of construction hereinafter described and claimed.

In the accompanying drawings, which form a part of this specification, I have illustrated a preferred embodiment of my invention, and in which:

Figure 1 is a perspective view of the device with the cover removed. Fig. 2 is a vertical cross-section through the center of the device. Fig. 3 is a fragmentary section taken on the line 3—3 of Fig. 2.

10 designates a cylindrical housing or casing which is suitably secured to a floor by means of angle plates 11. A hinged cover 12 is adapted to close the top of said casing. A circular bottom plate 13 of a size but slightly smaller than the bottom 14 of the casing is provided at the center thereof with a tubular cylindrical guide 15 extending vertically therefrom. The top of said

tubular guide is closed and provided with a rectangular passage 16 adapted to receive a screw or worm shaft 17 made by twisting a strip of metal. The lower end of said shaft projects through said rectangular passage 16 into the tubular guide 15 and is provided at its lower end with a stop 18 which prevents said shaft from leaving said guide. The upper end of said shaft is rigidly secured to the top of a tubular sleeve 19 closed at the upper end but open at the bottom and of a size to slidably engage the tubular guide 15. Rigidly secured to said sleeve 19 is a series of radially extending 70 brushes 20 whose outer ends are connected by a ring-shaped brush 21. The brushes have the shape of a wheel with spokes whose hub is rigidly secured to the sleeve 19. The tufts or bristles of the brushes extend 75 upwardly and have their upper ends in a horizontal plane passing above the button-shaped bearing 26 which is formed integral with the top of the sleeve 19. The circular bottom plate 13 is secured to the bottom 14 80 of the cylindrical casing by means of a bolt 23 extending from said bottom 14 through an aperture in the circular plate 13 which is fastened to said bottom by means of a thumb nut 24. A helical spring 25, encircling the tubular member 15 and the lower portion of the sleeve 19, is disposed between the bottom plate 13 and the brushes 20.

As clearly seen in Figs. 1 and 2, the upper edge of the cylindrical casing 10 extends for 90 a distance above the top of the bristles 22 and may be used as a scraper for cleaning the sole of the shoe.

Operation: From the foregoing description, the operation of the improved shoe cleaner will be easily understood. The cover 12 having been removed, the sole of the shoe is placed on the top of the sleeve 19 and rests on the bearing 26. The foot is firmly pressed downward against the tension 100 of the spring 25. The sleeve 19 will rotate and slide on the tubular member 15 by reason of the fact that the twisted metal shaft 17 is forced to pass through the stationary 105 rectangular slot 16 in the top of the tubular guide 15, thereby imparting a rotary motion to said sleeve. The brushes, being radially secured to said sleeve, will rotate in unison therewith. As soon as pressure is released, spring 25 will move the sleeve 19 upward 110 and the twisted metal shaft 17, passing through the rectangular slot 16, will now

impart rotary movement to the brushes in a direction contrary to the first rotation thereof. By moving the foot resting on the sleeve 19 up and down a few times, the shoe 5 will be rapidly and effectively brushed and cleaned. The top of the bristles extending above the sole of the shoe will engage the sides of the uppers and clean them. When it is desired to remove the dust and dirt 10 cumulated in the casing 10, the thumb nut 24 is removed and the bottom plate 13, on which the dust and dirt is collected, together with the brush, may be taken out, cleaned, and reinserted in position.

15 It is thus seen that I have designed an extremely simple shoe cleaning device, inexpensive of manufacture, which will rapidly and effectively clean the shoe with little muscular effort.

20 While I have shown the preferred construction as now known to me, I do not desire to confine myself to the specific embodiment as described, as various changes in the arrangement of the parts will suggest 25 themselves to those skilled in the art without departing from the spirit of my invention as claimed.

I claim:

1. A shoe cleaner comprising a cylindrical 30 housing, a hinged top cover therefor, a circular bottom plate removably mounted within said housing, a tubular guide extending vertically upward from the center of said bottom plate, said guide being closed 35 at the top and provided with a rectangular passage therein, a sleeve slidably mounted on said guide, a vertical helical shaft rigidly secured to said sleeve and mounted for longitudinal and rotary movement in said 40 passage, a plurality of horizontal brushes secured to said sleeve extending radially therefrom, and a helical spring encircling said guide and engaging said plate and said brushes.
- 45 2. A shoe cleaner comprising a housing, a hinged top cover therefor, a tubular guide extending upwardly from the bottom of said housing, said guide being provided with a nut at the top thereof, a sleeve slidably mounted on said guide, a vertical helical shaft rigidly secured to said sleeve and mounted for longitudinal and rotary movement in said nut, a plurality of horizontal 50 brushes secured to said sleeve and extending

radially therefrom, and a helical spring 55 encircling said guide and engaging said brushes to yieldingly hold the same in their upper position.

3. A shoe cleaner comprising a housing, a tubular guide mounted therein and extending vertically upward, a nut mounted at the top of said guide, a sleeve slidably mounted on said guide, a vertical helical shaft rigidly secured to said sleeve and mounted for longitudinal and rotary movement in said nut, a plurality of horizontal brushes secured to said sleeve, and a spring 65 for holding said brushes in their upper position.

4. A shoe cleaner comprising a frame, a 70 vertical guide, a sleeve slidably mounted on said guide, a helical vertical shaft rigidly secured to said sleeve, a nut mounted at the top of said guide and coöperating with said shaft to impart rotary movement to the latter, brush members rigidly mounted on said sleeve, and resilient means holding said members in their upper position.

5. A shoe cleaner comprising a frame, a vertical guide, a brush-supporting member 80 slidably mounted thereon, a horizontal brush, a vertical shaft rigidly secured to said brush-supporting member, means mounted on said guide and shaft for imparting to said shaft a rotary movement when 85 the said shaft is vertically reciprocated, and resilient means engaging said brush-supporting member for holding the same in its upper position.

6. A shoe cleaner comprising a guide, a 90 brush movably mounted thereon, for rotary motion in a horizontal plane, reciprocable means operated by the pressure of the shoe to be cleaned for imparting rotary movement to said brush, and resilient means for 95 moving said brush to normal position when the pressure on said means is released.

7. A shoe cleaner comprising a horizontal brush, means operated by the pressure of the shoe to be cleaned for rotating said brush 100 in a horizontal plane, and resilient means operatively connected to said brush for moving the same to normal position when the pressure on said brush is released.

In testimony whereof I have signed my 105 name to this specification.

MELVIN E. HILL.
